DESIGN FOR A CIGARETTE BOX OR LIKE RECEPTACLE

Forrest G. Purinton, Waterbury, Conn., assignor to The Patent Button Company, Waterbury,
Conn., a corporation of Connecticut

Application June 22, 1934, Serial No. 52,283

Term of patent 14 years

To all whom it may concern:

Be it known that I, Forrest G. Purinton, a citizen of the United States, residing at Waterbury, in the county of New Haven, State of Connecticut, have invented a new, original, and ornamental Design for Cigarette Boxes or Like Receptacles, of which the following is a specification, reference being had to the accompanying drawing, forming part thereof.

The drawing is a perspective view of a box showing my new design, the several areas or zones thereof being lined for contrasting colors, those lined for gold presenting a lustrous metallic appearance.

I claim:

The ornamental design for a cigarette box or like receptacle as shown and described.

FORREST G. PURINTON.
